(Cl. D9—2)

To all whom it may concern:

Be it known that I, John F. Finn, a citizen of the United States, residing at Burbank, county of Los Angeles, and State of California, have invented a new, original, and ornamental Design for a Molded Handle for Sweepers, Vacuum Cleaners, and Similar Articles, of which the following is a specification, reference being had to the accompanying drawing, forming part thereof.

Fig. 1 is a side elevation of the handle embodying my new design.

Fig. 2 is a bottom view of the handle.

Fig. 3 is a transverse section through the handle.

I claim:

The ornamental design for a molded handle for sweepers, vacuum cleaners and similar articles, substantially as shown.

JOHN F. FINN.
